UNITED STATES PATENT OFFICE.

GEORGE A. DONNELLY, OF CHICAGO, ILLINOIS.

DISPENSING APPARATUS.

No. 920,931.

Specification of Letters Patent.

Patented May 11, 1909.

Application filed October 5, 1908. Serial No. 456,108.

To all whom it may concern:

Be it known that I, GEORGE A. DONNELLY, a citizen of the United States, residing at Chicago, in the county of Cook and State of Illinois, have invented certain new and useful Improvements in Dispensing Apparatus, of which the following is a specification:

This invention relates to means for dispensing measured quantities of fluid or semi-fluid material, and is herein shown as embodied in a device that is particularly intended for dispensing liquid soap.

One of the objects of the invention is to provide improved means for positively and forcibly discharging the material, in order to obviate choking or clogging of the apparatus.

Another object is to simplify the construction of devices of this class, with a view to cheapness, increased durability, and freedom from liability to derangement.

A further object is to provide an improved bracket for supporting the device.

The invention also relates to the other improvements and advantages hereinafter set forth.

In the accompanying drawings, Figure 1 is a central sectional view of a soap dispenser embodying the features of my invention, said view being taken on line 1 1 of Fig. 4, a portion of the container being in elevation. Fig. 2 is a section taken on the plane of line 2 2 of Fig. 1. Fig. 3 is a section on the plane of line 3 3 of Fig. 1. Fig. 4 is a fragmentary front elevation.

The embodiment herein shown of my invention comprises a container 1, which may be in the form of a bottle, as shown, provided with a cap 2, which cap may have a vent 3 therein to admit air to the container to take the place of the fluid discharged. Said container is supported upon a base 4 which carries the valve mechanism that controls the flow of soap, an annular flange 5 extending upward from said base holding the container in place upon said base.

The valve mechanism comprises a cylinder 6 formed in the base 4, the bore of said cylinder being, in this instance, smaller at its forward end than at the rear, thereby forming a shoulder or annular valve seat 7. A port 8 connects the container 1 with the cylinder 6, and a discharge port 9 leads from a point slightly forward of the valve seat 7 to the front of the base 4. The rear end of the cylinder may be closed by a screw plug 10.

A plunger 11 is slidably mounted in the cylinder 6, the ends of said plunger being of different diameters to conform to the bore of the cylinder. A shoulder 12 on said plunger is arranged to be normally held against the shoulder or valve seat 7 by the action of a coiled spring 13. The plunger 11, in this instance, is hollow, a portion of the spring 13 lying within said plunger, the end of said spring opposite the piston being seated in a recess 14 formed on the screw plug 10.

An annular channel or depression 15 in the periphery of the forward end of the plunger 11 forms a space between said plunger and the cylinder wall, which space is adapted to be placed in communication with the larger end of the cylinder and the interior of the plunger 11, when the plunger 11 is moved away from its seat 7, through ports 16 extending through the walls of the plunger, said plunger, between the shoulder 12 and ports 16, being reduced in diameter to allow the fluid to flow from the ports 16 to the groove 15.

The stem 17 of the plunger 11 extends through the forward end of the cylinder 6 and carries a button 18 for convenience in moving said plunger. The shank of the button 18 lies within and frictionally engages the walls of an axial opening in the outer end of the stem 17.

The means for supporting the base 4 comprises, in the present instance, grooves 19 in which the arms 20 of a supporting bracket 21 are arranged to slide, a screw 22 extending through said bracket, and into the screw plug 10, preventing the base from being removed from said bracket. The bracket 21 may be fixed to a support in any suitable way as by screws 23.

In assembling the device, the plunger 11, with the spring 13 therein, is inserted through the rear end of the cylinder 6, the plug 10 screwed into said rear end of the cylinder, and the button 18 attached to the stem of the plunger.

In operation, when it is desired to draw a quantity of soap from the container 1, the plunger 11 is forced inward against the action of the coiled spring 13 to remove the shoulder 12 from the valve seat 7, when the liquid can flow from the interior of the plunger 11 through ports 16 into the groove 15 and out through the discharge port 9. After the rear end of the plunger has passed

the port 8, pressure is put upon the liquid to force it out as the inward movement of the plunger continues.

It will be seen that the plunger 11 cuts off communication between the container 1 and the cylinder by closing the port 8 at the beginning of its stroke, thus preventing the escape of more than a determined amount of liquid at each depression of the plunger 11.

10 If desired the bracket 21 may be inverted so as to dispose the attaching flange or base of said bracket at the rear of the container 1, as the arms 20 are adapted to engage in the grooves 19 in either position, it being understood that the screw 22 is dispensed with when the bracket is used in such inverted position.

Obviously changes in details of construction may be made from the embodiment herein shown without departing from the scope of the invention, wherefore I desire not to be limited to the exact construction shown and described.

I claim as my invention:

25 1. In dispensing apparatus, in combination, a cylinder having a discharge port and an annular valve seat, and a hollow plunger adapted to seat against said valve seat, said plunger having an annular peripheral depression in its end adjacent said discharge port to form a space between the plunger and the wall of said cylinder, said plunger having a port arranged to place the interior thereof in communication with said space.

35 2. In dispensing apparatus, in combination, a cylinder having an inlet port, a discharge port, and an annular valve seat therein, and a hollow plunger in said cylinder, a portion of said plunger being reduced 40 in diameter to form an annular shoulder arranged to engage said valve seat and forming a space between said portion and the cylinder communicating with the discharge port, said plunger having a port arranged to

45 place the inlet end of said cylinder and the

interior of said plunger in communication with said space, and said plunger being arranged to cut off the inlet port in its initial movement, whereby further movement of said plunger will positively force the material 50 in the inlet end of said cylinder through the port in said plunger into said space.

3. In dispensing apparatus, in combination, a cylinder, the bore of which is of smaller diameter at one end than at the other 55 to provide an annular valve seat, the smaller end of said cylinder having a discharge port; and a plunger having an annular shoulder thereon to seat against said valve seat, said plunger being peripherally grooved to form a 60 space communicating with said discharge port, said plunger having a port therein rearward of said shoulder, and said plunger being adapted to place said port in communication with said groove. 65

4. In dispensing apparatus, in combination, a container; a cylinder lying horizontally below and wholly outside of said container, said cylinder being of smaller diameter at one end than at the other to form an 70 annular valve seat, said cylinder having an inlet port in its larger end communicating with said container and a discharge port in its smaller end; and a hollow plunger in said cylinder having a shoulder arranged to lie 75 against said valve seat, the periphery of the smaller end of said plunger being grooved to form a space between said periphery and the interior of said cylinder, said plunger having a port adapted to place the interior of said 80 plunger in communication with said space when said plunger is slid to move said shoulder away from said valve seat; and means tending to hold the plunger in position to engage said shoulder with said valve 85 seat.

GEORGE A. DONNELLY.
